Atty's.

UNITED STATES PATENT OFFICE.

ARTHUR MILLER, OF CHICAGO, ILLINOIS.

CAR TANK.

Application filed July 25, 1927. Serial No. 208,276.

This invention relates to improvements in car tanks, and more especially to such a tank as commonly used in poultry cars.

In such tanks as heretofore made and used, difficulty is frequently encountered from water slopping or spilling out through the neck of the tank in transit. The rocking and shaking of the car causes a great deal of disturbance and splashing of the water inside the tank with the result that some of it splashes out through the neck of the tank around the plug.

Among the features of my invention is the provision of means to prevent such escape of water from such splashing.

Other features and advantages of my invention will appear more fully as I proceed with my specification.

In that form of device embodying the features of my invention shown in the accompanying drawings, Figure 1 is a vertical sectional view and Fig. 2 is a similar view on an enlarged scale showing one neck of the tank.

As shown in the drawings, 10 indicates a water tank as commonly arranged and supported inside of a car. The tank is provided with two filling necks 16, 16 and since these are similar I shall describe but one in detail.

The neck 16 is preferably provided with a plug 17 provided with a handle 17^a. The neck 16 of the tank is usually tapered, as shown.

18 indicates a collar attached to the inside of the neck by means of the rivets 19 and provided at its lower edge with an inwardly projecting flange 18^a. The lower end of the plug 17 is provided with a recess or rabbet 17^b adapted to accommodate the collar 18 and the lower end of the plug 17 preferably rests on the flange 18^a.

One of the advantages of my invention is that the collar with the flange 18^a can be readily attached to existing tanks.

In the operation of the device, the flange 18^a and the other parts prevent splashing and leakage of the water out around the plug 17.

The flange 18^a is preferably narrow enough so that the space confined thereby is not substantially smaller than the opening 50 of the neck at its smaller end. Ordinarily such necks are large enough so that a man may go through to enter the tank. Accordingly, if the space confined by the flange 18^a is not substantially smaller than the small end 55 of the neck, a man may pass through just as well when the collar and flange are in place.

While I have shown and described certain embodiments of my invention, it is to be understood that it is capable of many modifications. Changes, therefore, in the construction and arrangement may be made without departing from the spirit and scope of the invention disclosed in the appended 65 claim, in which it is my intention to claim all novelty in my invention as broadly as possible in view of the prior art.

What I claim is new, and desire to secure by Letters Patent, is:

In combination with a tank of the character described provided with a tapered neck and plug therefor, means for preventing water from leaking up through the neck around the plug, said means including, a 75 separate tapered collar adapted to fit in the inside of said neck and adjacent to the walls thereof, said collar having an integral inwardly projecting flange at its lower edge, and means for attaching said collar inside 80 of said neck to make a water-tight joint between said collar and said neck, said plug for said tank adapted to fit in said neck above said flange and provided with a rabbet to accommodate said collar.

In witness whereof, I have hereunto set my hand this 15th day of July, 1927.

ARTHUR MILLER.
